UNITED STATES PATENT OFFICE.

RICHARD O. BARLER, OF CHICAGO, ILLINOIS.

DESIGN FOR A BICYCLE-SADDLE.

SPECIFICATION forming part of Design No. 25,724, dated June 30, 1896.

Application filed April 25, 1896. Serial No. 589,129. Term of patent 7 years.

To all whom it may concern:

Be it known that I, RICHARD O. BARLER, a citizen of the United States, residing at Chicago, in the county of Cook and State of Illinois, have invented and produced a new and original Design for Saddles for Bicycles and Tricycles, of which the following is a specification, reference being had to the accompanying drawings, forming a part thereof.

10 This design relates to saddles for bicycles, the object being to provide a saddle that will be ornamental in appearance and presenting features which will readily distinguish it from the saddles now on the market.

15 In the accompanying drawings, Figure 1 is a bottom plan view of a saddle of my design, and Fig. 2 is a top plan view of the same.

The leading feature of my design consists in the forwardly-projecting parallel pommels 20 located on opposite sides of the median line of the saddle and the T-shaped opening in the body of the saddle.

A represents the saddle, which is preferably of the pneumatic variety and of a somewhat T shape in plan. Located centrally within the body of the saddle is the T-shaped slot, and at the forward end of the saddle and separated by one member of the T-shaped slot are the two horns or pommels B. The saddle in plan is also in the form of the letter 30 T, the rear end thereof being widened laterally with semicircular ends, and the pommels are integral with and project forwardly from the center of the front section of the body of the saddle. 35

What I claim is—

The design for a saddle substantially as shown and described.
